UNITED STATES PATENT OFFICE.

EDGAR E. TATLER, OF TRENTON, NEW JERSEY.

DESIGN FOR A SPINNER.

56,949.

Specification for Design.

Patented Jan. 18, 1921.

Application filed May 28, 1920. Serial No. 385,075. Term of patent 7 years.

To all whom it may concern:

Be it known that I, EDGAR E. TATLER, a citizen of the United States, residing in Trenton, in the county of Mercer, in the State of New Jersey, have invented a new, original, and ornamental Design for a Spinner, of which the following is a specification, reference being had to the accompanying drawing, forming a part hereof.

Figure 1 is a side elevation of a spinner of my design, and Fig. 2 is a top view thereof.

I claim—

The ornamental design for a spinner, as shown.

EDGAR E. TATLER.
